UNITED STATES PATENT OFFICE.

DAVID PRICE, OF PHILADELPHIA, PENNSYLVANIA.

DESIGN FOR A DOOR.

SPECIFICATION forming part of Design No. 29,043, dated July 12, 1898.

Application filed March 22, 1898. Serial No. 674,838. Term of patent 7 years.

To all whom it may concern:

Be it known that I, DAVID PRICE, a citizen of the United States of America, and a resident of Philadelphia, in the county of Philadelphia, State of Pennsylvania, have invented 5 a certain new and original Design for Doors, of which the following is a specification.

My invention relates to a design for a door which may be used singly or in pairs upon 10 bookcases, wardrobes, closets, &c., or, if desired, may be employed in connection with folding beds or other articles of furniture.

Referring to the accompanying drawings, Figure 1 illustrates a front elevation of a door 15 showing my new design, and Fig. 2 represents a transverse section on the line 2 2 of Fig. 1.

As shown in the drawings, the leading or 20 material feature of my design consists of a number of vertical ribs *a*, formed in the door

A and covered with a suitable material, so as to give the appearance of the backs of a stack of books, and horizontal cross-bars *b*, formed upon the door and arranged between the vertical ribs *a* to represent shelves upon which 25 the vertical ribs indicating the backs of a stack of books rest, the whole being inclosed within the frame of the door A by a glass plate C.

Having described my invention, what I 30 claim as new, and desire to secure by Letters Patent, is—

The design for a door, substantially as herein shown and described.

Signed by me at Philadelphia, in the county 35 of Philadelphia, State of Pennsylvania.

DAVID PRICE.
